UNITED STATES PATENT OFFICE.

JACOB SIMONIS AND HERMANN LOHRKE, OF CHICAGO, ILLINOIS.

DESIGN FOR A CALK FOR HORSESHOES.

SPECIFICATION forming part of Design No. 29,896, dated December 27, 1898.

Application filed November 4, 1898. Serial No. 695,510. Term of patent 7 years.

To all whom it may concern:

Be it known that we, JACOB SIMONIS, a citizen of the United States, and HERMANN LOHRKE, a subject of His Majesty the Emperor of Germany, residing at Chicago, Cook county, State of Illinois, have invented and produced a new and original Design or Conformation for Calks for Horseshoes, of which the following is a specification.

Figure 1 is a side view of the calk. Fig. 2 is a vertical cross-section, and Fig. 3 is a plan view.

As shown in the drawings, the leading or material features of our design consist of the rectangular body portion *c*, side ribs *a a*, and the centrally-disposed connecting rib or web *b*, said ribs extending vertically from or in the same plane with the body portion *c*. The edges of the ribs are beveled, as shown, and

the central rib is formed at right angles to 20 the side ribs, though it may be cast diagonally or at an acute angle thereto. The shank or stem *d* has formed thereon helicoidal threads *e*, which extend from the shoulder *f* to the outer end of said shank. 25

Having thus described our invention, what we claim as new, and desire to secure by Letters Patent, is—

The design for a calk for horseshoes substantially as herein shown and described. 30

In testimony whereof we affix our signatures in presence of two witnesses.

JACOB SIMONIS.
HERMANN LOHRKE.

Witnesses:

J. BUEHLER,
L. HANKE.
